ASSIGNORS TO THE STANLEY WORKS, OF NEW BRITAIN, CONNECTICUT, A CORPORA-
TION OF CONNECTICUT.

THUMB-LATCH.

1,334,739.

Specification of Letters Patent. Patented Mar. 23, 1920.

Application filed November 14, 1916. Serial No. 181,333.

To all whom it may concern:

Be it known that we, STUART W. PARSONS and ARCHIBALD D. WATERS, citizens of the United States, and residents of New Britain, in the county of Hartford and State of Connecticut, have invented certain new and useful Improvements in Thumb-Latches, of which the following is a specification.

The object of the invention is to produce a device of the character described in which provision is made for the operation of the latch by a thumb piece at both sides of the door. Heretofore the latch has been operable by a lifter having a thumb piece on but one side of the door, the other end of the lifter being bent down to form a handle.

In the drawings—

Figure 1 is a view of the device shown in place on a door.

Fig. 2 is a sectional view.

Fig. 3 is a view similar to Fig. 2, but showing the position of the parts when the thumb piece is being used to raise the latch.

Fig. 4 is a rear view of one face plate showing in transverse section the nested lifter bars.

Figs. 5 and 6 are detail perspective views showing the manner of assembling the lifter bars with their thumb pieces in the face plates.

Referring to the drawings—A denotes a door, and B, a door frame. C is the face plate of the latch. D, the latch bar pivoted as at d. E is a strap fastened to the door near its edge to hold the bar D rigidly in place but permitting of its up and down movement. F is the keeper on the door frame with which the latch bar is engaged and from which it is disengaged by lifter bars, the particular construction of which will be hereinafter described.

By reference to Figs. 2 and 3, it will be seen that there are similar face plates C, C', on both sides of the door. 5 denotes one lifter bar having the thumb piece 6 at its outer end. This lifter bar has a rocking support in the face plate C and extends through the door through an aperture in the opposite face plate C' and underlies the latch bar D. As will be seen from Figs. 4 and 5, the lifter bar 5 is of U-shape in cross section. The second lifter bar 10 has a rocking support in the face plate C' and fits within the U-shaped lifter bar 5, as clearly seen in Figs. 2, 3 and 4. The outer

end of the lifter bar 10 is shaped into the thumb piece 11.

By reference to Figs. 2 and 3, it will be apparent that when the thumb piece 6 is operated, the lifter bar 5 will raise the latch 60 D, acting directly on it; and that when the thumb piece 11 is operated, the lifter bar 10, fitted within the lifter bar 5, will raise the lifter bar 5 and so raise the latch D.

This arrangement provides a finished trim for each side of the door and permits of the operation of the latch bar by a thumb piece at either side of the door.

Notches, 20, are formed in the lower edge 70 of the lifter bars by spaced outwardly bent projections 21, and these notches fit down onto the edge of apertures in the face plates to provide the rocking support for the lifter bars. In order to assemble these 75 lifter bars with their face plates and hold them in position against accidental withdrawal, the apertures are enlarged at their upper edges and the latch bars are inserted upside down, as clearly seen in Fig. 6, and 80 then when the notches are brought into registering position with the edge of the aperture the lifter bar may be turned to right-side-up position, as clearly seen in Fig. 5.

Owing to the fact that doors vary in thickness, it is desirable to have the lifter bar 5, which is the direct actuator for the latch bar B, longitudinally adjustable through the face plate by providing a plurality of notches 20.

In accordance with the provisions of the patent statutes, we have described the principle of operation of our invention, together with the apparatus which we now 95 consider to represent the best embodiment thereof; but we desire to have it understood that the apparatus shown is only illustrative, and that the invention can be carried out by other means.

We claim as our invention:—

1. A latch including a plate having an aperture therethrough and adapted to be secured to one face of a door, said aperture being enlarged at a portion thereof, a latch 105 bar adapted to be pivotally mounted on the opposite face of said door, and a rockable actuator for said bar extending through said aperture and having spaced lateral projections to normally engage the opposite sides 110

of the plate adjacent the aperture and thereby prevent removal of the actuator from the plate, said projections being of a form to pass through the enlarged portion of the aperture when the actuator is partially rotated from its normal operative position relative to the plate whereby said actuator may be removed from the plate.

2. A latch including a plate having an aperture therethrough and adapted to be secured to one face of a door, said aperture being enlarged at its upper portion, a latch bar adapted to be pivotally mounted on the opposite face of said door, and a channel-shaped rockable actuator for said bar ex-

tending through said aperture and having spaced lateral projections extending from the longitudinal edges thereof to normally engage the opposite sides of the plate adjacent the aperture and thereby prevent removal of the actuator from the plate, said projections being of a form to pass through the enlarged upper portion of the aperture when the actuator is partially rotated from its normal operative position to an inverted position relative to the plate whereby said actuator may be removed from the plate.

STUART W. PARSONS.
ARCHIBALD D. WATERS.
